UNITED STATES PATENT OFFICE.

JACOB A. GRAFF, OF BROOKLYN, NEW YORK.

DESIGN FOR A TOY BANK.

SPECIFICATION forming part of Design No. 18,352, dated May 29, 1888.

Application filed October 1, 1887. Serial No. 251,246. Term of patent 3½ years.

To all whom it may concern:

Be it known that I, JACOB A. GRAFF, a citizen of the United States, and a resident of Brooklyn, in the county of Kings and State of New York, have invented and produced a certain new and original Design for a Toy Bank, of which the following is a specification.

The object of my invention is to produce an attractive design for children's money-banks, and to that end I have devised the receptacle which is hereinafter particularly set forth.

The design is shown in the accompanying drawing, which forms a part of this specification, and which represents my newly-designed toy bank in perspective.

My design involves the conception of a toy bank in the similitude of the conventional trunk, but distinguished from a mere miniature trunk in the particulars of having an oblong opening, C, in the lid or cover, the ends of the body having sunken panels and the lid having panel-work ornamented in the line of said oblong opening.

Referring to the drawing, A represents the body of the receptacle, and B its transversely-convex top. In the center of the top B there is formed a narrow oblong slit, C, and around the receptacle, near each end thereof, are representations of straps E, having buckles a, as shown. At F are representations of handles, and at G the representation of a lock. The ends of the receptacle have a border, D, raised above the surface, and sunken panels, and the lid has ornamented panel-work in the line of said opening.

Having thus described my invention, what I claim as new, and desire to secure by Letters Patent, is—

The design for a toy bank herein described and shown, the same consisting of an oblong box having the conventional representation of a lid and an oblong opening therein, and having conventional representations of buckled encircling leather straps and a lock, the ends of the body having sunken panels and the lid having ornamented panel-work.

Signed at New York, in the county of New York and State of New York, this 26th day of September, A. D. 1887.

JACOB A. GRAFF.
